WATER HEATING AND STORAGE SYSTEM

Harrison D. Sterrick, Pittsburgh, Pa.

Application February 9, 1935, Serial No. 5,765

2 Claims. (Cl. 122—18)

This invention relates to new and useful improvements in water heating and storage systems, and it is among the objects thereof to provide apparatus which shall be highly efficient in the heating of water as demanded by the system and which shall make use of substantially all of the heat of the burner through an arrangement of heat conducting and absorbing baffle members, provisions being also made to absorb the heat that is ordinarily lost through radiation from the storage and circulating system.

These and other objects of the invention will be more clearly understood from a consideration of the accompanying drawings constituting a part hereof in which like reference characters designate like parts and in which:

Fig. 1 is a front elevational view partially in section of a hot water storage and heating system embodying the principles of this invention;

Fig. 2 a plan view of a burner utilized in the apparatus shown in Fig. 1;

Fig. 3 a sectional elevation of a flow control device employed in the structure of Fig. 1;

Fig. 4 a cross-section of the burner taken along the line 4—4, Fig. 2;

Fig. 5 a cross-section of a modified form of circulation control valve;

Fig. 6 a plan view of the heating coil;

Fig. 7 a diagrammatic view of the top portion of the heating coil;

Fig. 8 a front elevation partially in section of a modified form of the device of Fig. 1;

Figs. 9, 10, 11, and 12 are cross-sectional views of special heater coil tubing;

Fig. 13 a plan view of the heater coil;

Fig. 14 a side elevation of a baffle member utilized in conjunction with the coil;

Fig. 15 a side elevation partially in section of still another modification of the heating and storage system;

Fig. 16 a plan view of a baffle strip employed in the manner hereinafter designated; and

Fig. 17 a sectional elevational view of a modified form of heater.

With reference to the structure shown in Figs. 1 to 7 inclusive of the drawings, the numeral 1 designates a hot water storage tank having an inlet connection 2 and an outlet connection 3 for attachment of helical coils 4 and 5, respectively, the helix 4 leading to a source of cold water supply 6 and the helix 5 to a heating coil 7 connected to a service line 8 from which hot water is withdrawn for use. Coil 5 is wound around the storage tank 1. A cylindrical housing 9 is disposed around the coil 5, the coil 4 around

the housing 9, and a second housing or casing 10 is disposed around the coil 4, the housing 10 having an opening or vent 11 at the top thereof.

It is to be noted that the end of the coiled pipe 4 extends into the storage tank to within a short distance of the bottom of the tank, this end being designated by the numeral 12. The lower end of the coil 5 is spirally wound as designated by the numeral 13, and a metal or refractory strip 14 is mounted in contact with the coil 13 to produce a maximum surface area for the absorption of heat which is conducted through strip 14 to the coil 13. The heater coil 7 is attached to the center of the spiral coil 13 and is disposed above a burner 15 connected to a source of gaseous or other fuel at 16. The coil 5 is connected to the spiral coil 13 at 17 and the heating coil 7 is connected to the spiral coil 13 at 18, Fig. 7. The burner 15 is preferably of the construction shown in Fig. 2 to provide a maximum burner area by the distribution of the burner openings 19 in the manner shown in Fig. 2.

The operation of the device shown in Figs. 1, 2, 4, 6, and 7 is briefly as follows: The heat of the burner 15 passes upwardly into and around coil 7, thence through the spiral coil 13 and follows the helical flue constituted by coil 5, the outer wall of tank 1 and the inner wall of the housing 9. The coils, 7, 13, and 5 form a large surface for the absorption of the heat from the burner 15 and in addition the baffle strip 14 of coil 13 and the walls of the tank 1 and housing 9 absorb heat from the products of combustion as they rise between the housing and the tank. The coil 5 is made to contact tank 1 and housing 9 so as to form a helical flue passage for the products of combustion, thus retarding the upward movement of the hot gases and allowing a maximum time for the absorption of the heat. The rate of this vertical movement of the heat can be controlled by the pitch of the coil 5 which must be sufficient to prevent any back pressure that might interfere with proper combustion at the burner 15. The heat from the housing 9 is absorbed by the cold water supply coil 4 to provide preheating of the water passing into the storage tank through the inlet connection 2. Housing 9 absorbs the heat radiated from tank 1, thus providing for maximum heat absorption to obtain the highest efficiency of the heat input.

The system shown in Fig. 1 may be used for so-called instantaneous heating or the burner may be so controlled that water in the storage tank is maintained at a given temperature and additional heat is supplied when the water is with-

drawn through the service connection 8, several methods of controlling the application of the heat being shown in the modification shown in Figs. 8 and 15.

5 In the structure shown in Fig. 8 the tank 1, inner housing 9 and outer housing 10 are the same as shown in Fig. 1. The cold water supply line 4 is coiled and passes into the storage tank at the top connection 2 as in Fig. 1 and 10 extends towards the bottom of the tank 1 as shown by the connection 12, the same as in Fig. 1, the numeral 6 designating the cold water supply line. The heater coil of Fig. 8, designated by the numeral 20, is of any of the constructions shown in 15 cross-sectional views, Figs. 9, 10, and 11, wherein tubing having integrally formed radiating fins 21 is utilized to provide maximum heating surfaces. Coil 20 is connected to tank 1 by a pipe 22 extending through the bottom of the tank to 20 a point near the top of the tank, the end of the vertical pipe being designated by the numeral 23. Burner 24 is provided beneath the coil 20, the burner being provided with a pilot flame 25 and with regular burner openings 26. A strip 27 25 which may be bronze or other metal of high heat conductivity is disposed between the storage tank 1 and housing 9 to form a helical flue 28 for the passage of the products of combustion. A metal strip 29, Figs. 13 and 14, may be disposed between 30 the coils of the heater coil 20 to provide heat absorbing surfaces where the coil itself is not provided with the fins 21 shown in Figs. 9 to 11.

The structure of Fig. 8 is of the circulating type employing a flow control device 30 which is 35 more clearly illustrated in Fig. 5 of the drawings, and consists of a T connection 31, one end of which is connected to the cold water supply coil 4 leading to the top of the tank; the other end to a source of cold water supply 6. Another T 32 40 is connected to the T 31 and an L 33 connects at the bottom of T 32, connection 34 and 35 being made with the T 32 and L 33, respectively. Connection 34 leads to the service line and 35 to the heater coil 20. A baffle plate 36 is disposed in the 45 T 31 and is provided with a central orifice 37 in which is connected a small diameter bent pipe 38 having an open end 39 in the flow passage of the coil line 35. The end of cold water line 6 projects into T 31 beyond the orifice 37 to produce a distorted path of flow.

50 In operation, the cold water supply is always in communication with the coil 4 leading to the top of the tank 1 and connection 35 is always established with the heater coil 20. As previously mentioned, the pilot 25 is burning continuously and the main burner is controlled by a thermostatic or valve of the conventional type. The heat of the pilot flame 25 causes the water in coil 20 to be heated and pass upwardly into storage tank 1. When the service connection 34 is closed, water passing upwardly in coil 20 is replaced by cold water passing through opening 37 of the T 31 through the small bent pipe 38 into the bottom of the coil. When water is drawn through the 60 service connection 34, a reverse flow will result through coil 20 to the connection 35, thence into T 32 and out through the service connection 34. This reverse flow is impinged against the opening 39 of the small pipe 38, thus preventing the withdrawal of cold water from the line 4 into the service line 34. By this construction, circulation from the coil to the tank and reversing of flow is effected without any movable valve mechanism.

75 A modification of the flow device of Fig. 5 is shown in Fig. 3 wherein a T 40 is provided with a

connection 41 leading to a heating coil, a connection 42 leading to a service line, and 43 connecting to a T of a water supply line.

In the structure shown in Fig. 15, the tank 1, inner housing 9 and outer housing 10 are the same as in Figs. 1 to 8. The water supply coil 4 is disposed between the inner and outer housings and is spirally arranged at the top, the spiral coil being designated by the numeral 44 and a connection extends to within the tank terminating at 12. A coil 5 is connected at the top of the tank at 3 as in Fig. 1 and passes around the exterior of the tank to a heater coil 45 having fins 46 as shown in Fig. 12. The water supply coil 4 is connected by a pipe 6 and the heater coil is 15 connected to a flow control device 47 having a connection 48 to a service faucet. A gas line 49 is connected to a burner 50 having a pilot flame 51 and a main burner portion 52.

In operation, coil 45 is heated by the pilot flame 20 51 and the heated water passes into tank 1 at the top thereof, cold water being supplied through coil 4. The baffles 46 and the spiral coil 44 at the top of the tank together with the arrangement of spiral coils and housings as in Fig. 1 will 25 provide a maximum heat absorbing area for the products of combustion.

When the service faucet 48 is opened, hot water is withdrawn from the tank 1 through coil 45, and thence through the flow control mechanism 30 47. This flow of water will actuate a valve in the housing 53 to open the gas line 49 causing the main burner 52 to be ignited and the coil 45 to be subjected to intense heat so that the water 35 passing through the coil to use is of maximum temperature.

Fig. 17 shows a heater comprising a housing 60 having a burner 61 at the bottom thereof. A water pipe 62 is disposed centrally of the housing and a fin 63 is secured between the housing and 40 pipe. The fin 63 is helically wound and attached to pipe 62 by brazing or welding to conduct the heat absorbed by the fin to the pipe. The fin extends from pipe 62 to the inner wall of housing 60 forming a helical flue for the products of com- 45 bustion.

It is evident from the foregoing description of the invention that water heating systems made in accordance therewith provide for the efficient use of fuel and maintain maximum supply of hot 50 water by use of the pilot flame which is readily increased in temperature by the main burner when the hot water is withdrawn at the service connection.

Although several embodiments of the invention have been herein illustrated and described, it 55 will be obvious to those skilled in the art that various modifications may be made in the details of construction without departing from the principles herein set forth.

I claim:

1. A water heating and storage system comprising a storage tank and a pair of cylindrical housings disposed around said tank in spaced relation therewith, a water supply line in the form of a helix disposed between said cylindrical housings entering the top of the storage tank and extending to adjacent the bottom thereof, and a helical pipe connected to the top of the storage tank extending to the bottom thereof, a heating coil of pyramidal shape below the tank terminating into a spiral at the top and connected to the bottom of the helical pipe connected to the top of the tank, and a burner below said heating coil.

2. A water heating and storage system comprising a storage tank and a pair of cylindrical housings disposed around said tank in spaced relation therewith, a water supply line in the form 5 of a helix disposed between said cylindrical housings entering the top of the storage tank and extending to adjacent the bottom thereof, and a helical pipe connected to the top of the storage

tank extending to the bottom thereof, a heating coil of pyramidal shape below the tank terminating into a spiral at the top and connected to the bottom of the helical pipe connected to the top of the tank, and a burner disposed below said coil 5 and having burner openings coextensive with the maximum diameter of the heating coil.

HARRISON D. STERRICK.
